UNITED STATES PATENT OFFICE.

REGINALD L. S. DOGGETT, OF EAST ORANGE, NEW JERSEY.

VARNISH OR COLOR CUP.

1,255,990.

Specification of Letters Patent.

Patented Feb. 12, 1918.

Application filed July 26, 1917. Serial No. 182,841.

To all whom it may concern:

Be it known that I, REGINALD L. S. DOGGETT, a citizen of the United States, and a resident of East Orange, in the county of Essex and State of New Jersey, have invented certain new and useful Improvements in Varnish or Color Cups, of which the following is a specification.

This invention relates to improvements in varnish or color cups, and has for its principal object the provision of a simple and inexpensive device forming a holder for varnish or color containers and a receptacle for the wipings from brushes used in applying the contents of the containers carried in the holder.

A further object of the invention is to provide a receptacle for brush wipings which may be readily cleaned, and which is adapted to form a holder or support for cans, containers, or receptacles of varnishes, paints, or the like.

In the drawings, Figure 1 is a perspective view of a combined container holder and wiping receptacle, with a varnish or color container supported therein;

Fig. 2 is a similar view with the varnish or color container removed;

Fig. 3 is a vertical sectional view of the holder showing a container supported therein; and

Fig. 4 is a top plan view of the holder with the container removed.

In the embodiment of the invention shown in the drawings the combined container holder and wiping receptacle is formed with a substantially rectangular body portion having side walls 1, a rear wall 2, and a front wall 3. The lower portion of the body part 1 forms a well or receptacle 4 for the brush wipings. The side walls 1 are formed with ledges or inwardly projecting portions 5, forming shoulders 6, at a point below the upper edges of the side walls 1 adapted to form seats or supports for the bottom of a varnish or color container 7. The front wall 3 of the body portion of the holder is cut away, as shown at 8, in Figs. 2 and 4, from its upper edge to a point below the shoulders or seats 6 on the upper sides of the ledges or projecting portions 5. A spout or chute for the brush wipings is held to the front wall 3 and comprises an upwardly and outwardly extending front wall 9, extending from the lower edge of the cut-away portion 8 of the front wall 3

to a point above the level of the upper edge of the varnish or color container 7. The upwardly and outwardly extending wall 9 of the wiping spout or chute is connected with the vertical edges of the cut-away portions 8 of the front wall 3 by side walls 10, the upper edges of which are preferably curved inwardly and downwardly from the straight wiping edge 11 of the spout wall 9 to the upper edge of the front wall 3.

A handle 12 is rigidly held to the rear wall 2 of the body portion of the holder. The handle 12 is preferably formed with curved portions at both its upper and lower ends to adapt the holder to be carried with the fingers of the hand of the user passed through the handle, or to be carried with the bottom of the holder resting on the palm of the hand with the thumb passed through the handle 12, as may be desired.

While the body portion 1 of the container has been shown of substantially rectangular form, it will be obvious that the body portion may be formed of substantially cylindrical or other shape to adapt the holder to receive containers of various shapes. It will also be obvious that any suitable means may be employed for supporting the bottom of the container at a point above the bottom of the wiping receptacle or well 4, such as inwardly extending flanges or brackets held to the walls or bottom of the body portion.

From the foregoing it will be observed that original containers of varnishes, paints, etc., may be placed in the holder and the contents thereof used directly from said original containers without the necessity of transferring the varnishes or paints from the original containers to separate cups or buckets, thus avoiding waste and contamination of the materials. It will also be observed that when the contents of the container have been used the container may be discarded and a new container substituted, thus avoiding the necessity of cleaning a varnish cup or bucket, and the liability of contaminating a fresh supply of varnish or paint by successive use of the same container. It will also be seen that the combined holder and wiping receptacle may be employed to hold containers formed of cardboard, paper, or similar materials, which containers may be discarded after being once used.

By extending the spout or chute for the wipings from a point below the bottom of the container to a point above the level of the

upper edge of the container, it will be seen that the brush may be wiped across the upper edge of the spout without danger of the wipings falling back into the container, as all the wipings will flow down the spout or chute and into the well 4 beneath the container. A further feature of the invention consists in forming the body portion of the holder with relatively low side walls thus facilitating access to the well or receptacle for the wipings for cleaning purposes. It will also be observed that the spout or chute for the wipings is entirely open at one side and may therefore be readily cleaned.

15. What I claim is:—

1. A device of the class described, comprising a body portion having a wiping-receiving well at its lower end and formed with interiorly arranged shoulders adapted to support a container above said well, one wall of said body portion being formed with an opening extending from its upper edge to a point below said shoulders, and a spout held to said wall and extending upwardly from the lower edge of said opening, said spout being formed with an open side

adjacent the body portion and having a brush-wiping edge at its upper end.

2. A device of the class described, comprising a wiping receptacle provided with means at the sides thereof for supporting the bottom of a container within the upper end of said receptacle, a container seated on said supporting means, and a chute communicating with the receptacle at a point below the bottom of the container, said chute extending upwardly above the upper end of the container and having a brush-wiping edge at its upper end.

3. A device of the class described, comprising a container holder formed with a seat in its upper end for the lower end of a container and having a wiping receiving well therein below said seat, a chute extending upwardly from said well above the walls of the holder and having a brush-wiping edge at its upper end, and a handle secured to said holder.

In testimony whereof I hereunto affix my signature.

REGINALD L. S. DOGGETT.
